Application filed August 27, 1894. Serial No. 521,466. Term of patent 3½ years.

To all whom it may concern:

Be it known that I, LOUIS CLÉMENCET, a citizen of France, residing at West Hoboken, in the county of Hudson and State of New Jersey, have invented and produced a new and original Design for Wall-Paper, of which the following is a specification.

The design consists of branches of the pine tree with pine cones placed irregularly over the surface of the paper with a spider web work forming a back ground for the design as represented in the accompanying drawing.

The border or upper portion of the design is formed of a continuous branch of pine

trees with pine cones and spider web back ground below the branch and a striped band forming the bottom of the border as shown in the drawing.

What I claim is—

The design for wall paper herein shown and described.
